WITNESS:

UNITED STATES PATENT OFFICE.

OSCAR CARL PAPIN, OF DUBUQUE, IOWA.

FLUSH-TANK FILLING VALVE.

Application filed August 4, 1923. Serial No. 655,617.

To all whom it may concern:

Be it known that I, OSCAR C. PAPIN, a citizen of the United States, residing at Dubuque, in the county of Dubuque and State of Iowa, have invented new and useful Improvements in Flush-Tank Filling Valves, of which the following is a specification.

My invention has reference to valve mechanism employed in closet tanks.

10 My object is to simplify and improve the existing art by producing a filling valve for closet tanks that may be cheaply constructed, easily applied and which shall be accurate and positive in action.

15 To the attainment of the foregoing and other objects which will present themselves as the nature of the invention progresses, reference is to be had to the drawings which accompany and which form part of this 20 application.

In the drawings:—

Figure 1 is a sectional view through a filling tank for closets illustrating the application of the improvement.

25 Figure 2 is an approximately central vertical longitudinal sectional view through the improvement.

Figure 3 is a top plan view thereof.

Figure 4 illustrates details.

30 Referring now to the drawings in detail, the numeral 1 designates a filling or flush tank for closets of the usual construction. The water outlet 2 in the bottom of the tank 1 is controlled by the usual valve actuated in the usual manner.

35 The water inlet pipe, indicated by the numeral 3 is flanged adjacent to its bottom and is, of course, connected to the usual water conducting pipe whereby water under pressure is let into the tank 1. The top of the inlet pipe is, of course, open and the upper portion of the said tank is surrounded by a pressure resisting chamber in the nature of a tube 4. The tube has its bottom connected 40 to the pipe 3 and its body spaced from the side pipe in any desired manner, such for instance, as by the employment of one or more spiders 17 between the pipe and tube. The lower portion of the tube 4 is provided 45 with series of apertures 5 forming water outlets, and the upper portion of the said tube

is threaded. Screwed on the threads is the flange of a frusto-conical cap member 6. On the top of the inlet pipe there is a compressible valve seat 7 for a valve 8. The 55 valve 8 has a lower flat face which is preferably provided with a ring washer to engage the compressible element on the seat 7. The upper portion of the valve is complementary to the inner flared surface of the cap member 6. The valve 8 is provided with a stem 9 that extends through a central opening in the cap and to this stem there is loosely pivoted a lever 10. On the cap there is an upstanding arm 11 to which one end of the 60 lever 10 is pivoted. Also on the cap directly opposite the arm 11 there is an angle bracket 12, and to the upstanding or vertical arm of this bracket there is pivoted, as at 13, the rod or arm 14 for the float 65 valve 15. Pivoted to the outer end of the lever 10 and to the inner end of the rod 14 there is a link 16.

When water from the flush tank is let through its outlet 2 the float will sink with 70 the overflowing water, causing the swinging of the rod or arm 14 which influences the link to swing the lever 10 to raise the valve 8 to unseated position. This, of course, permits of the inflow of water through the pipe 75 3. The water contacts the flat under face of the cap and is thus directed downwardly into the pressure reducing chamber 4. The water finds an outlet through the apertures 5 at and adjacent to the bottom of the chamber 4.

It is believed that the foregoing description when taken in connection with the drawings will fully set forth the construction and advantages of the improvement, 80 but I desire it to be understood that I am entitled to such changes therefrom as fall within the scope of what I claim.

Having described the invention, I 85 claim:—

The combination with a water tank having a valved outlet and a water inlet pipe, of a tubular water pressure reducing chamber surrounding the upper part of the inlet pipe and having an open top and a closed 90 bottom which is secured to the inlet pipe, said chamber, at its bottom and for a dis-

2
tance thereabove being apertured, spiders spacing the chamber from the inlet pipe, a compressible valve for closing the mouth of the inlet pipe and seated on the top of the chamber, a cap threadedly engaging the top of the chamber and holding the valve thereon, a float carrying rod pivotally con-

nected with the chamber, and means between the chamber and rod, and actuated by the rise and fall of the said rod for permitting the seating and unseating of the valve.

In testimony whereof I affix my signature.

OSCAR CARL PAPIN.
